DUAL PURPOSE PULL STRIP

Donald G. Magill, Great Neck, N. Y., assignor to American Can Company, New York, N. Y., a corporation of New Jersey

Application May 5, 1955, Serial No. 506,259

7 Claims. (Cl. 229—51)

The present invention relates to fibre containers having pull strips for opening them and has particular reference to such a strip which also serves as a means for protecting an exposed fibrous portion or edge of the container.

In packaging certain products in fibre containers having interiorly exposed raw edges, such as score lines and lapped side seam edges, considerable difficulty is often experienced in preventing ingredients of the product from seeping through these raw edges into the fibre material of which the containers are made. Volatile, oily, greasy or liquid ingredients if permitted to seep into the fibre material weakens the container and often causes its failure as a container. Such containers also are often difficult to open without the aid of a tool such as a knife or the like to cut through the fibre material.

An object of the instant invention is the provision in a fibre container for products of the above suggested nature, of a pull strip which serves a dual purpose of protecting a raw exposed edge in the container and also serves as a means for easily opening the container to gain access to its contents.

Another object is the provision of such a dual purpose pull strip which may be readily and economically applied to a composite container, i. e. a container having a fibre body and metal end closures.

Another object is the provision of such a dual purpose pull strip which is inexpensive and which may be economically and easily attached to the containers during their manufacture without interfering with subsequent manufacturing operations.

Numerous other objects and advantages of the invention will be apparent as it is better understood from the following description, which, taken in connection with the accompanying drawings, discloses a preferred embodiment thereof.

Referring to the drawings:

Figure 1 is a perspective view of a composite fibre-metal container embodying the instant invention, parts being broken away;

Figs. 2 and 3 are enlarged sectional views respectively taken substantially along planes indicated by the lines 2—2 and 3—3 in Fig. 1, parts being broken away;

Fig. 4 is a perspective view similar to Fig. 1 and showing a modified form of the invention;

Figs. 5 and 6 are enlarged sectional views respectively taken substantially along planes indicated by the lines 5—5 and 6—6 in Fig. 4, parts being broken away;

Fig. 7 is a fragmentary enlarged perspective view of a portion of the upper marginal edge portion of the container shown in Fig. 4, the view showing the edge portion prior to assembly with the top closure of the container;

Fig. 8 is a perspective view of the upper end of a container similar to that shown in Fig. 1 and illustrating a further modified form of the invention;

2

Fig. 9 is an enlarged sectional view as taken substantially along a plane indicated by the lines 9—9 in Fig. 8; and

Fig. 10 is a fragmentary sectional view taken substantially along the line 10—10 in Fig. 9.

As a preferred or exemplary embodiment of the instant invention Figs. 1, 2 and 3 of the drawings illustrate a composite container for products such as biscuit dough, pie dough, frozen citrus concentrates and the like products. Such a composite container preferably comprises a fibre material body 21 and sheet metal top and bottom closure members 22 made from tin plate, black iron or the like sheet material and secured to the body in suitable end seams 23.

15 The fibre body 21 preferably is made from a one-piece flat blank formed into cylindrical shape to produce a tubular cylindrical body having opposing marginal edge or lap portions 24, 25 overlapped and secured together by adhesive 26 to produce a lap side seam 27 which holds 20 the body together. The inner and outer surfaces of the body 21 preferably are protected by a gasproof, moisture-proof, waterproof and greaseproof coating material such as a metal foil (tin or aluminum), a microcrystalline wax, plastics as Saran (polyvinylidene chloride), Mylar 25 (oriented polyester resin) or other suitable materials. However the inner and outer laps or marginal edge portions 24, 25 of the side seam 27 terminate in raw edges 29 (Figs. 2 and 3).

In order to protect the raw edge 29 of the inner lap 30 24 against seepage thereinto of the container contents, this edge is covered or enclosed in a narrow strip or tape 31 of high tensile strength, such for example as oil and moisture resistant regenerated cellulose (cellophane) material. The tape 31 is adhesively secured to the raw edge 29 and to the immediately adjacent marginal portions thereof on both sides of the fibre material as best shown in Fig. 3. The tape 31 extends the full length of the edge 29 on the inner lap 24. Adjacent the top end of the container the tape 31 is bent outwardly back on 35 itself and extends transversely of the side seam 27 between the inner and outer laps 24, 25, and terminating beyond the seam and on the outside of the container, in a tail or pull tab 33 where it is clear of the seam during the formation of the seam in the manufacture of the container.

40 While the container is in use as a holder of a product, the tape 31 shields and thus protects the inner raw edge 29 of the side seam 27. When it is desired to open the container to release the product a pull on the tab 33 in a direction toward and thence along the side seam tears 45 the seam across to the inner raw edge 29 and then tears the seam longitudinally along the inner raw edge for the full length of the container body thus opening the body. During this seam tearing action the tape 31 is also torn off the inner raw edge 29 but this is intended since the 50 protection of the raw edge is no longer needed. Thus the tape 31 serves the dual purpose of protecting the inner raw edge of the side seam 27 while required and also acts as a means of opening the container to gain access to its contents.

55 Figs. 4, 5, 6 and 7 illustrate a strip or tape 35 similar to the tape 31 of the preferred form of the invention, with the tape 35 applied flatwise against the inner surface of the container body 21 and along the side seam 27 for its entire length in 60 overlapping relation thereto so that it covers and shields the raw edge 29 of the inner lap portion of the seam as best shown in Fig. 6. In this form of the invention the tape 35 extends through an opening 36 (Fig. 7) in the container body 21 at the upper end of the body, and 65 terminates in a pull tab 37 located outside the body. The opening 36 in the body preferably is formed as a small 70

notch which is so located as to be incorporated in the end seam 23 of the container so as to avoid direct communication therethrough between the interior and the exterior of the container. The bottom of the notch preferably is located so as to provide for the incorporation of the tape 35 in the end seam 23 in such a manner that it can be readily pulled out.

Hence while the filled container is in use, the tape 35 overlapping the side seam 27 protects the inner raw edge 29 of the seam against permeation by the contents of the container and when the container is to be opened, a pull on the tab 37 withdraws the tape from the end seam 23 and tears the container body longitudinally along the side seam 27 to open the body to expose its contents. Thus as in the preferred form of the invention, the tape 35 serves the same dual purpose.

In another modified form of the invention as illustrated in Figs. 8, 9 and 10, a tape 41 similar to the tape 31 of the preferred form, is utilized to cover and protect an annular raw edged score line 42 which preferably extends entirely around the body 21 adjacent its upper end. The score line 42 is formed in the inside surface of the container body. The tape 41 overlaps and extends along the score line and is adhesively secured to the inner surface of the body. At the side seam 27 one end of the tape covers the aforesaid raw edge 29 of the inner lap 24 so as to entirely cover the score line 42 at this edge. The other or opposite end of the tape 41 extends between the inner and outer laps 24, 25 of the seam as shown in Figs. 9 and 10 and projects and terminates outside the body in a pull tab 43.

Hence while the container is in use prior to opening, the tape 41 overlapping and shielding the score line 42 protects the raw edges of the score line against ingress of the container contents and when the container is to be opened, a pull on the tab 43 readily tears the body 21 transversely across the side seam 27 and circumferentially along the score line 42 to completely sever the top end of the container from the body 21 so as to facilitate access to the contents of the container. Thus as in the preferred form of the invention the tape 41 serves the dual purpose of protecting the described raw edges of the body and score line and also serving to open the body by a severing operation.

It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. A container for products having ingredients deleterious to raw exposed edges of fibrous materials, comprising a tubular fibre body having end members secured thereto in end seams, said fibre body having an exposed raw edge on the interior surface thereof, and a protective tape adhesively secured over said raw edge on the interior surface of said body, said tape terminating at one end in a pull tab extending through and disposed exteriorly of said body, whereby said tape serves the dual purpose of protecting said exposed raw edge on the interior body

surface against the ingress of the container contents after the container is filled, and of tearing said body open along a line contiguous to said raw edge to gain access to said product.

5. A container of the character defined in claim 1 wherein said tape is composed of oil and moisture resistant regenerated cellulose material of high tensile strength.

3. A container of the character defined in claim 1 wherein said fibre body is provided with a lapped side seam the inner lap of which terminates in said exposed raw edge on the interior surface of said body, and wherein said tape covers the full extent of said raw edge and said exterior pull tab is disposed immediately adjacent said side seam for tearing said body open therealong.

4. A container of the character defined in claim 3 wherein said tape is secured to said raw edge and the adjacent marginal edge portions of said inner lap and at one end of said seam is reversely bent upon itself to extend between the laps of said seam and terminates on the outside of said body adjacent said seam for tearing transversely across said seam and thereafter longitudinally therealong to disrupt said seam and open said container.

5. A container of the character defined in claim 3 wherein said tape is secured to said raw edge and to the adjacent inner surfaces of said inner lap and said body so as to bridge said raw edge and wherein one end of said tape terminates in a pull tab projecting through and disposed exteriorly of said body adjacent said side seam for tearing through said body along said seam to open said container.

6. A container of the character defined in claim 5 wherein said body is provided with end closures secured thereto in end seams and wherein an end of said body adjacent one of said end seams and said side seam is provided with an opening through which said tape extends, whereby said tape is incorporated in said one end seam for withdrawal therefrom by said pull tab as an incident to opening said container.

7. A container of the character defined in claim 1 wherein the interior surface of said body is provided with a peripheral score line including said exposed raw edge and extending entirely around said body, and wherein said tape is adhesively secured over and throughout said score line to protect said raw edge thereof, one end of said tape extending to the outside of said body and terminating in a pull tab for tearing said body along said score line to open said container.
